by *J. Roberts* Atty.

UNITED STATES PATENT OFFICE.

HENRY P. CLAUSEN, OF MOUNT VERNON, AND CHARLES L. GOODRUM, OF NEW YORK, N. Y., ASSIGNORS TO WESTERN ELECTRIC COMPANY, INCORPORATED, A CORPORATION OF NEW YORK.

TELEPHONE-EXCHANGE SYSTEM.

Application filed July 19, 1919. Serial No. 311,958.

To all whom it may concern:

Be it known that we, HENRY P. CLAUSEN and CHARLES L. GOODRUM, citizens of the United States, residing at Mount Vernon, in 5 the county of Westchester and State of New York, and at New York, in the county of New York and State of New York, respectively, have invented certain new and useful Improvements in Telephone-Exchange Sys- 10 tems, of which the following is a full, clear, concise, and exact description.

This invention relates to improvements in telephone exchange systems and has particular reference to a special service feature 15 therefor.

It is desirable, especially during certain times, that incoming calls to a private automatic exchange should be connected to the desired substation and also to a special attendant's position in such manner that the attendant may ascertain if the called subscriber answers and, if not, then converse with the calling party.

An object of the invention is to provide 25 means whereby a special attendant's position may be caused to be connected, during certain hours, to an established connection.

In accordance with this object, a time controlled mechanism is operable, when a 30 calling line is connected to a called line, to cause an auxiliary trunk hunting switch at an attendant's position to connect the attendant's substation apparatus to the calling and called lines. A signaling current is 35 then simultaneously applied to the called and the attendant's substation and the attendant may first determine without affecting the connection whether or not the called party answers. If not, the attendant's line 40 may then be connected to the calling line to permit the attendant to converse with the calling party.

The inventive idea involved is capable of 45 receiving a variety of expressions one of which, for the purpose of illustrating the invention, is shown in the accompanying drawing; but it is to be expressly understood that said drawing is employed merely for the purpose of facilitating the description 50 of the invention as a whole and not to define the limits thereof, reference being had to the appended claims for this purpose.

In the drawing, the figure illustrates

diagrammatically a circuit and mechanism 55 arranged in accordance with the invention.

Briefly, when a subscriber at substation A desires a connection to substation B, a final selector or connector switch C is operated, in a manner to later appear, to connect the 60 calling with the called party. During certain hours when it is known or surmised that subscribers within the exchange are absent, it is desirable that the calling and called substations A and B be connected to 65 substation D at a special attendant's position whereby the attendant may be connected to the calling and called lines in order to definitely determine whether or not the called party answers and if he does not, 70 then converse with the calling party. In order to accomplish this purpose, use is preferably made of a trunk hunting switch E operated by mechanism F to hunt for the 75 calling and called lines. The mechanism F is preferably associated with a clock (not shown) and made common to a plurality of switches C. This mechanism comprises an annular conducting member f' and individual conducting segments f² corresponding 80 in number to the hours of the day. The grounded wiper f³ is adapted to engage segments f² and by inserting a plug or plugs f⁴ between one or a number of segments f² and the annular conducting member f', it 85 will be apparent that when the wiper f³ engages segments f², the ground will be applied to conductor f⁵. When one of the connector switches is operated, the ground on this conductor is extended to the switch E 90 and causes the same to hunt for the calling and called lines and upon finding the same signaling current will be simultaneously applied to substations B and D. The attendant at substation D may then respond and 95 listen in to determine whether or not the called subscriber answers.

It is believed that the invention will now be fully understood from the following detailed description of the operation. When a subscriber at substation A initiates a call, 100 automatic switches, such as one conventionally shown at G are operated in a manner well-known in the art to extend the calling line to one of the connector switches C. Connector switch C is similar in its operation 105 to the connector switch shown in the patent to Goodrum #1,231,013 issued June

26, 1917. A circuit is then established for line relay 1 of the selected switch C which circuit is traceable from grounded battery, right winding of relay 1, brush 2, apparatus 5 at substation A, brush 3 and left winding of relay 1 to ground. Relay 1, in energizing establishes a circuit for slow-to-release relay 4, and at its back contact and armature removes the ground from the third wire and 10 brush 18 which had up to this time marked the switch as idle. The switch is now in position to receive the impulses corresponding to the tens digit of the wanted line and in response to the first impulse, relay 1 15 retracts its armature to establish a circuit for slow-to-release relay 5 extending from grounded battery, winding of said relay, front contact and right armature of relay 4 and back contact and armature of relay 1 to 20 ground. Relay 5 energizes and establishes a circuit for escape magnet 6 extending from grounded battery, front contact and right armature of relay 5, winding of magnet 6 and back contact and armature of ringing 25 relay 7 to ground. Relays 4 and 5 maintain their armatures attracted during the transmission of impulses. In response to each interruption in the line, a circuit is established for primary stepping magnet 8 30 extending from grounded battery, winding of said magnet, side-switch wiper 9 in position 1, front contact and right armature of relay 4 and back contact and armature of relay 1 to ground. Magnet 8 operates 35 to step brushes 10, 11 and 12 of switch C in a group selecting movement. At the termination of the first set of impulses, relay 1 remains energized and opens the circuit for relay 5 which, upon releasing, breaks the 40 energizing circuit for escape magnet 6. This magnet then releases and moves the side-switch wipers into position 2. The second set of impulses now transmitted will operate the secondary stepping magnet 13 45 over a circuit extending from grounded battery, winding of said magnet, side-switch wiper 9 in position 2 and from thence over the previously described circuit to ground at the armature of relay 1. Relay 5 again releases to open the energizing circuit of escape magnet 6, but if the called line is busy 50 this magnet, being slow to release, will not deenergize before a circuit is established for the release magnet 14. This circuit is traceable from grounded battery, right winding 55 of said magnet, right armature and back contact of relay 15, off-normal contact 16 which closes upon the first step of the switch, left armature and back contact of relay 5, side-switch wiper 16 in position 2, brush 60 12 and terminal 17 to ground. Magnet 14 locks up over a circuit extending from ground, left winding of said magnet, left armature and front contact of said magnet, front contact and left armature of relay 4, 65

brush 18, to grounded battery at a preceding switch such as shown in Fig. 2 of the above mentioned patent granted to C. L. Goodrum. In energizing, magnet 14 operates to return switch C to normal position and at the same time applies a busy tone to the calling subscriber's line. The calling subscriber upon hearing the busy tone, replaces his receiver upon its switchhook and thereby restores the other switch or switches in a well-known manner. 70 75

Assuming that the called line is idle, and that at the time the call is made, there is no ground upon conductor f^5 , magnet 14 will fail to energize upon the release of relay 5 and escape magnet 6 will therefore deenergize to move the side-switch wipers into position 3. A circuit will then be established for relay 5 extending from grounded battery, winding of said relay, side-switch wiper 9 in position 3 and front contact and armature of relay 1 to ground. Relay 5 again establishes an energizing circuit for escape magnet 6 but the side-switch wipers will remain in position 3. Energization of magnet 6 applies ringing current from a suitable source through the front contact and armature of magnet 6, winding of relay 7, side-switch wiper 19 in position 3, brush 11, apparatus at substation B including the ringer, brush 10, side-switch wiper 20 in position 3, front contact and armature of relay 1 to ground. Sufficient current does not pass through relay 7 to energize the same until the called subscriber responds at which time relay 7 attracts its armature and opens the energizing circuit for magnet 6. This magnet then releases and moves the side-switch wipers into position 4 whereupon conversation may proceed between the calling and called subscribers, talking current being applied to the called line from relay 15. At the end of the conversation, the replacing of the receiver upon its switchhook at substation A returns the switches to normal in the same manner previously referred to. 90 95 100 105 110

Let it now be assumed that when substation B is called, wiper f^3 of mechanism F is in engagement with one of the segments f^2 , which is electrically connected by plug f^4 to the conducting member f' . When switch C is stepped from its normal position, the off-normal contact 21 is closed with the result that a circuit is established for slow-to-release relay 22 of switch E extending from grounded battery, winding of said relay, upper armature and back contact of stepping relay 23, off-normal contact 21, conductor f^6 , member f' , segment f^2 and wiper f^3 to ground. Relay 22 attracts its armatures and establishes a self-interrupting circuit for stepping relay 23 extending from grounded battery, upper armature and front contact of relay 22, winding, upper arma- 115 120 125 130

ture and back contact of relay 23 and from thence to ground at the wiper ¹⁰ f³. Relay 23 operates to step the brushes of switch E over the terminal bank of said switch until 5 test terminal 24 to which the ground at the wiper ¹⁵ f³ is extended through off-normal contact 21 and conductor 25, is reached. Relay 22, being slow-to-release, will maintain its armatures attracted during the stepping of 10 the switch. The ground upon the terminal 24 will maintain relay 23 energized and thus prevent further stepping of the switch, the same being held in its set position by means of holding pawl 26. When side-switch 15 wipers 16 and 19 of switch C reach their third positions and ringing current through relay 7 is applied to the called line, this ringing current will also be simultaneously applied to the line of substation D through 20 the brushes of switch E and thus signal the attendant at said substation. The attendant after waiting a reasonable length of time may respond by removing the receiver from its switchhook which will close a circuit 25 through the condenser 27 at substation D and thereby increase the flow of signaling current to such an extent that relay 7 will attract its armature and the side-switch wipers will be passed into position 4 as 30 heretofore described. The attendant may then listen in on the circuit without disturbing it. If the called subscriber does not respond, the attendant may, after an interval, press a key 28 to close the line circuit 35 and establish a locking circuit for relay 29 which will maintain key 28 in its operated position. The attendant at substation D may now converse with the calling party and inform him of the absence of the sub- 40 scriber at substation B. The calling subscriber will then replace his receiver upon its switchhook with the result that the switches employed in establishing the connection between substations A and B will 45 be restored to normal. When switch C reaches normal and the off-normal contact 21 is opened, the holding circuit for relays 22 and 23 is opened. Relay 22, in releasing its lower armature, disengages pawl 26 from 50 teeth of the shaft E and this switch then returns to its normal position.

What is claimed is:

1. In a telephone system, calling and called lines, an attendant's position, switching means for interconnecting said calling and called lines, and means automatically operated simultaneously with said switching means during predetermined intervals for connecting said attendant's position to said calling and called lines.
2. In a telephone system, calling and called lines, an attendant's position, switching means for interconnecting said calling and called lines, and means automatically operated during predetermined intervals for connecting said attendant's position to said calling and called lines.

connecting said attendant's position to said calling and called lines when the same are interconnected and means thereupon operated for simultaneously signaling said called line and attendant's position. 70

3. In a telephone system, calling and called lines, an attendant's position, switching means for interconnecting said calling and called lines, a switch automatically operated to connect said attendant's position to said calling and called lines when the same are interconnected and means thereupon operated for simultaneously signaling said called line and attendant's position. 75

4. In a telephone system, calling and called lines, an attendant's position, switching means for interconnecting said calling and called lines, means for connecting said attendant's position to said calling and called lines when the same are interconnected, means for controlling the operation of the last-named means only during certain intervals, and means for signaling said attendant's position after the same is connected to said calling and called lines. 80

5. In a telephone system, calling and called lines, an attendant's position, switching means for interconnecting said calling and called lines, means automatically operated simultaneously with said switching means for connecting said attendant's position to said calling and called lines and means for simultaneously signaling said called line and attendant's position after 100 the same are connected. 95

6. In a telephone system, calling and called lines, an attendant's position, a connector switch operable to interconnect said calling and called lines, an automatic switch for connecting said attendant's position to said calling and called lines, mechanism operable during predetermined intervals to permit of the operation of said automatic switch, means under the control of said connector switch for connecting said mechanism with said automatic switch whereby the latter is operated, and a source of ringing current at said connector switch for simultaneously signaling the called line and said attendant's position when the connector and automatic switches have been connected to said called line. 105 110

7. In a telephone system, calling and called lines, an attendant's position, switching means for interconnecting said calling and called lines, means for connecting said attendant's position to said calling and called lines, and time controlled means for controlling the operation of the last-named means. 115 120

8. In a telephone system, calling and called lines, an attendant's position, switching means for interconnecting said calling and called lines, means operated simultane- 125 130

ously with said switching means for connecting said attendant's position to said calling and called lines, and time controlled means for controlling the operation of the 5 last-named means.

9. In a telephone system, calling and called lines, an attendant's position, a switch operable during predetermined intervals for connecting said attendant's position to 10 terminals of the calling and called lines, and switching means for interconnecting said calling and called lines and for con-

trolling the movement of said switch into engagement with said terminals.

10. In a telephone system, calling and 15 called lines, an attendant's position, switching means for interconnecting said calling and called lines, and means automatically operated to connect said attendant's position to said calling and called lines. 20

In witness whereof, we hereunto subscribe our names this 17th day of July A. D., 1919.

HENRY P. CLAUSEN.

CHARLES L. GOODRUM.
